(57) **CLAIM**

The ornamental design of a flow control ring as shown and described.

DESCRIPTION

FIG. 1 is a perspective view of the flow control ring, showing our new design;

FIG. 2 is a bottom perspective view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof; and,

FIG. 9 is a cross section taken from FIG. 1.
